UNITED STATES PATENT OFFICE.

ANDREW S. CALHOUN, OF EAST LIVERPOOL, OHIO.

DRILL-JAR.

1,177,379.

Specification of Letters Patent.

Patented Mar. 28, 1916.

Application filed December 18, 1915. Serial No. 67,687.

To all whom it may concern:

Be it known that I, ANDREW S. CALHOUN, a citizen of the United States, residing at East Liverpool, in the county of Columbiana 5 and State of Ohio, have invented certain new and useful Improvements in Drill-Jars, of which the following is a specification, reference being had therein to the accompanying drawing.

10 This invention relates to drill jars and is in the nature of an improvement upon the device shown and described in Letters Patent No. 1,154,483, granted to me Sept. 21, 1915.

15 The first object of the invention is to provide means to prevent the rotation and wabbling of the plunger and at the same time to insure a quick and free action thereof without cramping or binding of the same.

20 A second object of the invention is to provide a plunger head which will not cushion when it strikes water during its downward movement and thereby retard the efficient action of the plunger.

25 In the accompanying drawings, Figure 1 is an elevation of the device, partly in section; Fig. 2 is a cross section on the line 2—2 of Fig. 1, looking in the direction of the arrows; Fig. 3 is a cross section on the 30 line 3—3 of Fig. 1, looking in the direction of the arrows; and Fig. 4 is an inverted perspective view of the plunger head.

In the embodiment of the invention, as shown in the present drawings, 1 indicates 35 the casing in which the plunger operates, this casing having a chamber 2 therein. The casing here shown is cylindrical in configuration on the outside and oval or elliptical in configuration on the inside. The outside of the casing, however, may conform in 40 configuration to the inside, if desired, thereby making both the outside and the inside of the casing oval or elliptical. At 3 is shown a socket adapted to receive a reamer, 45 drill or other tool. An intermediate angular portion is shown at 4 to receive a wrench.

The casing has a series of narrow vertically formed slots therein, as shown at 5, these 50 slots permitting the free circulation of the water or other liquid transversely through the casing and around the plunger. By this arrangement, when the plunger is actuated any water contained in the casing will be thrown outwardly through the slots 5 and 55 thus prevent the resistance of the water from affecting the free operation of the de-

vice. The casing terminates in a suitable knocking head, as shown at 6, this knocking head having an oval or elliptical opening, as shown at 7, therein. Reciprocating within this opening is a plunger 8 which corresponds in shape with the said opening 7 and is so mounted therein as to have a free and unobstructed movement therethrough. The upper end of the plunger 8 is provided with the usual head 9 having a tapered threaded terminal 10 of the usual form to receive the shackle or coupling for the operating rope or cable. The head 9 is provided with the usual angular portion 11 to receive an operating wrench to hold the head while the cable is being coupled thereto. The lower end of the plunger 8 terminates in an enlarged head 12 which, as here shown, is substantially oval or elliptical. The major axis 70 of this head is substantially equal in length to the major axis of the inside of said casing, thereby insuring a close fit of the parts, as shown at 13. These adjacent parts of the plunger head and casing act as coöperating 75 guides to prevent the rotation of the head within the casing. The length of the minor axis of this head is less than that of the minor axis of the inside of the casing, forming thereby spaces, as shown at 14, between the outside of the head and the inside of the casing. It will be noticed that the slots 5 within the casing connect these spaces with the outside, the slots facing the elongated 80 sides of the said oval head. It is to be understood, however, that although the drawings show an oval structure it is within the scope of the invention to provide guiding means for the head, as shown at 13, and spaces, as shown at 14, without regard to the 85 shape of the said head or the inside of said casing. The lower portion of this head tapers, as shown at 15, forming a cutting edge 16 which is substantially of the same length as the major axis of the body portion of the head. This tapered portion has therein a series of longitudinal grooves or corrugations 17, as shown, and the purpose of which will be set forth later.

In the operation of the device when the head 9 is reciprocated to produce the drilling effect the plunger 8 will be guided in its opening 7, the plunger and opening coöperating to prevent relative rotation thereof but allowing the free reciprocation of the plunger. The plunger head 12 is also suitably guided, thereby preventing strains from 100 105 110

being put upon the plunger, eliminating the cramping thereof and insuring a free and easy movement, as well as preventing rotation. As the plunger head reciprocates the tapered portion thereof will cut through the water, whereby retardation of the device is prevented owing to the elimination of the cushioning effect which would result if the plunger head were flat. The corrugations 10 also assist in this operation and in addition aid in preventing the rotation of the plunger within its casing. If the device is to be employed for actuating a drill, the casing and the socket carrying the drill will operate vertically. Where a reamer is used the device will be rotated. It is obvious that the parts 1 and 9 can move relatively to each other in a vertical direction, but must move together in the same direction when the device is rotated.

It will be seen that I have provided a device in which the plunger will reciprocate freely and easily within its opening without rotating or unduly wabbling and in which 25 there will be no danger of the plunger becoming cramped within its opening and thereby causing the same to break. Furthermore, I have provided a novel head for the plunger which successfully wedges itself 30 through water, forcing the same out through suitable slots. This head also prevents the rotation of the plunger and keeps it in axial alinement in its opening. It will also be noted that the plunger works without binding 35 and is loose enough within the casing and opening to relieve vibrations. The slots 5, spaces 14 and tapered head 15 all co-operate to produce a very efficient and quickly acting device. The water is wedged 40 by the falling plunger head and is forced upwardly through the spaces 14 and out through the slots 5.

My device is very durable as the strains 45 are entirely eliminated from the plunger working in the opening 7.

While I have shown and described one embodiment of my invention it will be understood that this has been chosen for the 50 purposes of illustration only, and that I do not desire to be limited to the details of construction shown and described, for obvious modifications will occur to a person skilled in the art.

Having thus fully described my invention, what I claim as new and desire to secure by Letters Patent, is:—

1. In a drill jar, a casing, a plunger adapted to reciprocate in said casing, a head for said plunger, said casing and said head 60 having parts co-operating to prevent the rotation of said plunger, and a portion of said head being spaced from said casing a substantial distance.

2. In a drill jar, a casing, a plunger adapted to reciprocate in said casing, said

plunger having a head tapering to an edge at its lower end, and means comprising portions of the head and casing to prevent the rotation of said plunger in said casing.

3. In a drill jar, a casing, a plunger 70 adapted to reciprocate in said casing, said plunger having a head tapering to an edge at its lower end, longitudinally extending corrugations on said tapered head, and means comprising portions of the head and 75 casing to prevent the rotation of said plunger in said casing.

4. In a drill jar, a casing, a plunger adapted to reciprocate in said casing, said plunger having a head, and longitudinally 80 extending corrugations upon said head.

5. In a drill jar, a casing, a plunger adapted to reciprocate in said casing, said plunger having a flattened head, and longitudinally 85 extending corrugations upon said head.

6. In a drill jar, a casing, a plunger adapted to reciprocate in said casing, said plunger having a head tapered at its lower 90 end, and longitudinally extending corrugations upon said tapered portion.

7. In a drill jar, a casing, a plunger adapted to reciprocate in said casing, said plunger having a head tapering to an edge at its lower end, and longitudinally extending 95 corrugations upon said tapered portion.

8. In a drill jar, a casing, a plunger adapted to reciprocate in said casing, said plunger having a head, said head tapering to an edge at its lower end, longitudinally 100 extending corrugations upon said head, said head being spaced from said casing a substantial distance, means comprising portions of the head and casing to prevent the rotation of said plunger and said casing, and 105 slots located in said casing.

9. In a drill jar, a casing having a knocking head, an opening in said head, a plunger slidably mounted in said opening, means comprising portions of said plunger and 110 said head to prevent the rotation of said plunger in said opening, said plunger having a head at its lower end within the casing, and means comprising portions of the 115 plunger head and casing to prevent the rotation of the plunger and its head and the cramping of the plunger within said opening.

10. In a drill jar, a casing having an oval interior and a knocking head, an oval opening in said head, an oval plunger slidably mounted in said opening, thereby preventing the rotation of said plunger within said opening, said plunger having an oval head at its lower end within the casing, whereby 120 relative rotation between the casing and head is prevented and the plunger is kept 125 in axial alinement with its opening and prevented from cramping or binding.

11. In a drill jar, a casing having an oval 130

interior and a knocking head, a plunger adapted to reciprocate through an opening in said head, said plunger having an oval head at its lower end in engagement with the interior of said casing, whereby rotation of the said plunger head is prevented, and said plunger head tapering to an edge at its lower end.

12. In a drill jar, a casing having an oval interior, a plunger adapted to reciprocate in

said casing, said plunger having an oval head at its lower end, said oval head being in engagement with the interior of said casing at its ends, whereby relative rotation is prevented, and the sides of said plunger head being spaced a substantial distance from the surface of said interior.

15. In testimony whereof I affix my signature.

ANDREW S. CALHOUN.
